UNITED STATES PATENT OFFICE.

BRUNO ADLER, OF DRESDEN, GERMANY.

SPRAY CARBURETOR FOR INTERNAL-COMBUSTION ENGINES.

Application filed August 22, 1922. Serial No. 583,582.

To all whom it may concern:

Be it known that I, BRUNO ADLER, a citizen of the German Republic, residing at Dresden, Germany, have invented certain new and useful Improvements in Spray Carburetors for Internal-Combustion Engines, of which the following is a specification.

This invention has for its object an improvement in spraying carburetors in order 10 to render the same capable, if desired, of automatically drawing the fuel from the main reservoir.

By means of a channel which connects the passage which admits air to the main fuel 15 nozzle and leads to the float chamber a vacuum is produced in the float chamber which, however, is lower than that which exists in the main nozzle.

In order to make the carburetor available 20 for use with either atmospheric or sub-atmospheric pressure in the float chamber, an adjustable tickler is provided.

One form of the invention is illustrated 25 on the accompanying drawing in which:

Fig. 1 is a longitudinal section of the carburetor on the line 1—1 of Fig. 2,

Fig. 2 is a section on the line 2—2 of Fig. 1.

The body of the carburetor, indicated at 30 32, forms the main air passage. At one side the body has an enlargement 30 in which a tapered opening 2 is bored. In this tapered opening a plug 6 is fitted. A passage 1 is bored transversely through this enlargement, 35 the inner end of this passage terminating adjacent the edge of the throttle valve when the latter is closed. This passage supplies fuel for idling and its outer end is closed by the plug 31.

40 A passage 3 is bored through both walls of the main air passage, its inner end entering the bore 2. In this passage is inserted a main nozzle 5, the orifice of which discharges in the main air passage, in the restricted portion of the venturi 4 inserted therein. The plug 6 is bored longitudinally as at 11 and has transverse openings 8 and 12 bored at its lower and upper ends respectively. In the lower end of the bore 11 45 is inserted a calibrated plug 7 which forms the main fuel orifice. In the bore 12 is inserted a second calibrated plug 10 which determines the fuel feed item. The passage 8 connects the bore 11 and the main nozzle 5.

55 As shown on the drawing the plug 6 does

not completely fill the bore 2 and a series of small openings 9 connects the bore 11 with the passage thus formed. Above the normal fuel level, a passage 15 opens into this unfilled space, the purpose of which will be 60 described subsequently. A float chamber 13 containing the float 14 surrounds the carburetor body. The float 14 controls the admission of fuel to the float chamber in any desired manner, the normal fuel level being 65 indicated by the line L—L.

The passage 15 communicates with the float chamber through a calibrated opening 16 and with the atmosphere by means of a 70 calibrated opening 17.

Above the opening 16 is placed a reducing valve 18 in the form of a disc, the lift of which is limited by the snap ring 19 and the weight of which determines the vacuum 75 which may be imposed on the float chamber.

When it is desired to use atmospheric pressure in the float chamber the calibrated 75 plug 16 is replaced by a solid plug.

Behind the carburetor I employ a tickler 80 22; this tickler operates in a guide 20 and is maintained in raised position by a spring 21. The movement of the tickler is determined by a pin 23 which operates in slots 24 and 25 in the guide 20. On the stem of the tickler is formed a valve 26. If it be 85 desired to use atmospheric pressure in the carburetor the pin 23 is turned into the slot 24 so that the valve 26 is held open in the raised position of the tickler. For use as a lifting carburetor the pin is turned into the 90 slot 25 so that the valve is allowed to seat when the tickler is raised.

The operation of the device will be obvious from the foregoing description of the structure. At small throttle openings fuel 95 is drawn to the orifice of the plug 7 and the orifice of the plug 10, mixed with the air coming from the passage 15 into the main air passage of the carburetor. At high speed operation the fuel flow only through the plug 7, mixes with air coming through the orifices at 9 and the mixture flowing back from the passage 1 and is sprayed into the main air passage through the orifices of the nozzle 5. It will be obvious that by selecting proper sizes of the calibrated plugs at 7, 10, 16 and 17, proper mixture for the various operating conditions of the associated engine may be obtained. As is well known 105 in carburetors of this type, the flow of air 110

through the passage 15 and the opening 9 serves to prevent the undue enrichment at high engine speeds.

The depression which causes the air flow through the passage 15 lifts the valve 18 and is communicated to the interior of the float chamber. The differential between this pressure and the atmospheric pressure on the fuel in the main reservoir serves to feed fuel to the float chamber whenever the valve is opened by the fall of the float.

If the fuel is to be supplied to the carburetor by gravity or other pressure, the tickler will be turned so that the pin operates in the slot 24 and the opening at 16 will be closed by a solid plug. Under these conditions atmospheric pressure is maintained in the float chamber.

Having thus described my invention, I claim:

In combination with a carburetor having a float chamber and a mixture passage, a conduit connecting said mixture passage and float chamber, an air inlet orifice in said conduit and a tickler having a valve on its stem and means for normally holding said tickler raised and alternative means for fixing the raised position of the tickler so that in one raised position the valve is held open and in the other the valve is closed.

In testimony whereof I affix my signature in presence of two witnesses.

BRUNO ADLER.

Witnesses:

FRANZ SCHOLZY,
RUDOLPH FRICKE.
